UNITED STATES PATENT OFFICE

RUSSELL R. WATERMAN, OF LONG BEACH, CALIFORNIA, ASSIGNOR TO FARMERS' NATIONAL BANK OF GREENVILLE, OHIO, OF GREENVILLE, OHIO, A CORPORATION OF OHIO, TRUSTEE

FUEL-ATOMIZING NOZZLE

Application filed June 15, 1926. Serial No. 116,104.

My invention relates to fuel atomizing nozzles and the principal objects of my invention are; first, to provide an atomizing nozzle which has a compound atomizing action; 5 second, to provide an atomizing nozzle which is new and novel in its construction; and, third, to provide an atomizing nozzle which is very simple and economical of construction, easy to install, efficient in its action and 10 which will not readily deteriorate or get out of order.

With these and other objects in view, as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part 20 of this application in which:

Figure 1 is a sectional view through the atomizing nozzle and shown in connection with a fragmentary portion of a vaporizer, 25 and Fig. 2 is a sectional view through line 2-2 of Fig. 1.

Similar characters of reference refer to similar parts and portions throughout the different views of the drawings.

30 The fuel discharge tube 1, ejector tube 2, and the air nozzle 3 constitute the principal parts and portions of the atomizing nozzle.

The air nozzle 3 is a hollow cylinder, the central bore 3a of which is curved and tapered 35 from near the middle of its length to the bottom end thereof and toward the axis. The exterior of the air nozzle is threaded for about one-half of its length, the remainder of the periphery being of a slightly larger 40 diameter than the threaded portion, thus forming a shoulder 3b which engages a ledge 4a of a boss 4 which is formed on the vaporizer to support the complete atomizer nozzle.

The ejector tube 2 has a broad flange 2a 45 extending radially from the one end thereof. The flange 2a is secured upon the upper end of the boss 4, permitting the ejector tube 2 to extend into the bore 3a of the air nozzle 3 and having an air chamber 5 between the 50 boss 4 and the ejector tube 2. The outside

diameter of the ejector tube 2 at its upper end is enlarged but is smaller than the diameter of the bore 3a of the air nozzle 3 and as it enters the air nozzle this diameter is reduced, thus forming an inwardly inclined channel 55 for air when the parts are assembled, the ejector tube 2 extending into the air nozzle 3 for about three-quarters the length of the air nozzle. A plurality of small apertures 2b are provided through the walls of the 60 ejector tube 2 directly beneath the flange 2a.

The fuel discharge tube 1 is closed at its upper end and is provided with a broad flange 1a which extends radially from the walls at substantially the middle portion intermediate the ends thereof. The flange 1a is secured upon the flange 2a, the open end of the fuel discharge tube 1 extending into and for about two-thirds the length of the ejector tube 2. The interior portion of the fuel discharge 70 tube 1 is reduced in diameter where it extends into the reduced diameter portion of the ejector tube 2. A boss 1b is provided on one side of the fuel discharge tube 1 near the closed end thereof and above the flange 1a. The boss 1b is provided with an aperture 1c 75 which opens into the central orifice of the fuel discharge tube 1. The outer end of the aperture 1c is tapped to receive the end of the conventional fuel line 6 from which fuel 80 is supplied under little or no pressure.

An air intake pipe 7 provided on the one side of the boss 4 opens into the air chamber 5. A small aperture 8 is provided in the wall of the fuel discharge tube 1, beginning at the central orifice of the fuel discharge tube 1 near the closed end thereof and opposite the aperture 1c, which aperture extends down and out so as to open into the top of the air passage 85 surrounding the fuel discharge tube 1. A small aperture 9 is provided at the one side of the boss 4 providing a passage or drain from the air intake pipe 7 to the vaporizer for any moisture caused by condensation in the air as it passes toward and into the atomizer. The air then passes from the air intake pipe 7 into the air chamber 5 where the greater portion of it is forced around the ejector tube 2 and out through the bore 3a 90 of the air nozzle 3, atomizing and mixing the 100

particles of air and fuel which have been forced from the ejector tube 2. This forcing of the air and fuel from the ejector tube 2 is caused by passage of a small portion of the air from the air chamber 5 through the aperture 2b into the ejector tube 2, this air mixing with the fuel that is flowing from the fuel discharge tube 1. Fuel is conducted into the fuel discharge tube 1 by means of the fuel line 6. A very small portion of the air passing around the ejector tube 2 is conducted by means of the aperture 8 into the central orifice of the tube 1 overcoming any great vacuum therein and permitting the escape of the fuel therefrom.

15 Though I have shown and described a particular construction, combination and arrangement of parts and portions, I do not wish to be limited to this particular construction, combination and arrangement but desire to include in the scope of my invention the construction, combination and arrangement substantially as set forth in the appended claims.

20 Having thus described my invention, what I claim as new and desire to secure by Letters Patent is:

25 1. In a fuel atomizer, an oil discharge tube closed at one end, an oil supply tube communicating with the closed end thereof and positioned at right angles thereto, a tubular ejector member surrounding said oil discharge tube, forming therewith a closed outer end of the injector member and spaced from the inner end thereof and provided with a plurality of air inlets near its closed end and backwardly from the discharge end of the oil discharge tube and an air channel around the same for supplying said inlets, 30 and a air nozzle surrounding the extended end of said ejector member and spaced therefrom and supplied from said channel.

35 2. In a fuel atomizer, an oil discharge tube, closed at one end, an oil supply tube communicating with the closed end thereof and positioned at right angles thereto, a tubular ejector member surrounding said oil discharge tube, forming therewith a closed outer end of the injector member and spaced from the inner end thereof and provided with a plurality of air inlets near its closed end and backwardly from the discharge end of the oil discharge tube and an air channel around the same for supplying said inlets, an air 40 nozzle surrounding the extended end of said ejector member and spaced therefrom and supplied from said channel, and air inlet means communicating with the interior of said ejector member and with the interior 45 of said air nozzle.

50 3. In a fuel atomizer, an ejector nozzle provided in its side walls near one end with a plurality of air inlet orifices, a fuel oil discharge nozzle extending into said end 55 of the ejector nozzle, fitting tightly therein,

substantially aligned therewith and extending beyond the orifices and spaced with its end inwardly from the discharge end of the ejector nozzle, an air nozzle surrounding the ejector nozzle and extending beyond the inner discharge end thereof, and an air supply conductor communicating directly with the interior of the air nozzle and directly with said orifices.

55 4. In a fuel atomizer, an ejector nozzle provided in its side walls near one end with a plurality of orifices, a fuel oil discharge nozzle extending into said end of the ejector nozzle, fitting tightly therein, substantially aligned therewith and extending beyond the orifices and inwardly from the opposite end thereof, an air nozzle surrounding the ejector nozzle and extending beyond the inner discharge end thereof, and an air supply conductor communicating with the interior of the air nozzle and with said orifices, the inner end of the space between the air nozzle and the ejector nozzle communicating through the side with the inner end of the fuel discharge nozzle.

60 5. In a fuel atomizer of the class described, a fuel oil discharge nozzle, an ejector nozzle surrounding said fuel oil discharge nozzle, an air nozzle surrounding the ejector nozzle and extending beyond the discharge end of the latter, and an air supply means communicating with the inner end of said air nozzle and the inner end of said ejector nozzle, said fuel oil discharge nozzle having a small air passage communicating with said air supply means from the inner end of the fuel oil discharge nozzle.

65 In testimony whereof, I have hereunto set my hand at Los Angeles, California, this 8th day of June, 1926.

RUSSELL R. WATERMAN.
